Design No. 18,460, dated July 17, 1888.

UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S BLOUSE.

SPECIFICATION forming part of Design No. 18,460, dated July 17, 1888.

Application filed June 15, 1888. Serial No. 277,268. Term of patent 3½ years.

To all whom it may concern:

Be it known that I, HENRIETTA F. DUKE, of the city, county, and State of New York, have invented and produced a new and original Design for a Pattern of a Lady's Blouse; and I do hereby declare that the engraved prints accompanying this specification convey to any one accustomed to using paper patterns a clear understanding of how a garment made up by the pattern will appear.

The design shows full fronts displaying a deep smocking above the bust between two lines of shirrings and fullness at the neck and shoulders; a full back exhibiting smocking and shirrings corresponding with the front;

flat straps upon the shoulders; a deep rolling collar; long full sleeves with smocked cuffs falling in frills at the hands, and a belt drawing in the fullness at the waist, the skirt falling with flounce effect below the belt.

What I claim as my invention, and desire to secure by Letters Patent, is—

The design for a lady's blouse, as shown in the engraved prints accompanying this specification.

HENRIETTA F. DUKE.
